SAFETY SWITCH

Frederick Leonard Lade, Vancouver, British Columbia, Canada

Application March 5, 1938, Serial No. 194,144

1 Claim. (Cl. 200—82)

My invention relates to improvements in safety switches which are particularly adapted for use with oil burners. The object of the invention is to provide means whereby an increase or a decrease of pressure in the oil supply line between the pump and the burner will cause the switch to open and shut off the current to the motor which operates the pump. A still further object is to provide means whereby the burning of oil which may accumulate below the burner will break the electric circuit.

In oil burner installations, the presence of water in the oil supply line will cause a drop in pressure on the discharge side of the pump as soon as the water reaches the gears of the pump and dirt or other solid obstruction between the pump and the burner will increase the pressure, rendering the operation of the burner unsafe until the flow from supply to burner jet is rectified and it is with a view to shutting off the operation of the burner under unsafe conditions that the present invention is designed.

The invention consists essentially of a cylinder having a plunger, which plunger is movable in response to abnormal pressure in a supply line, and a switch rockingly mounted upon a shaft adapted to be opened by the movement of the plunger from its normal position, as will be more fully described in the following specification and shown in the accompanying drawing, in which—

Fig. 1 is a front elevational view of the invention.

Fig. 2 is a sectional view taken on the line 2—2 of Figure 1.

Fig. 3 is a diagrammatic view showing the various switch positions.

In the drawing like characters of reference indicate corresponding parts in each figure.

The numeral 1 indicates a switch base consisting of a horizontal plate 2 and a back panel 3. Extending downwardly below the plate 2 is a cylinder 4 connected at its lower end by a pipe 5 to the supply line 6 of an oil burner of a furnace, not shown. A plunger 7 having a connecting rod 8 is fitted within the cylinder and is provided with a spring 9 to force the plunger downward, the force of such downward thrust being adjusted by a nut 10 at the head of the cylinder. The upper end of the rod 8 is provided with a toothed rack 11, the purpose of which will hereinafter appear.

A discharge outlet 12 is provided adjacent the upper end of the cylinder 4, which is fitted with a branch pipe 13 leading to a suitable point

of discharge, to relieve the cylinder of any fluid passing the plunger, or pushing the plunger beyond the branch pipe connection.

A knife switch 14, having a hingedly mounted blade 15, is supported upon the horizontal plate 2 and a lever 16 is pivotally mounted as at 17 to extend through said plate to provide a lower portion 18, which is adapted to be connected by a cord 19 carried through the base of the furnace in such a position that it may be burned and the tension released in the event of abnormal heat or flame within the furnace. The upper portion 20 of the lever 16 is connected by an insulated link 21 to the free end of the switch blade 15 and a tension spring 22 is attached to said upper lever portion 20 to withdraw the blade in case of rupture of the pull cord 19.

Extending forwardly from the back panel 3 are stub shafts 23 and 24. The shaft 23 is fitted with a sleeve 25 to which is secured a pinion 26 in mesh with the toothed rack 11 and a gear 27 which engages a small gear 28 mounted upon a sleeve 29 upon the stub shaft 24. The sleeve 29 supports axially a clip 30 in which a mercury switch 31 is carried. The switch 31 is provided with two terminals 32 and 33, the enclosed ends of which are immersed to close the circuit, when in normal position as shown in Figures 1 and 2.

The switch circuit includes wires 34 and 35. The wire 34 connects with the mercury switch terminal 32, the wire 35 connects with the lower terminal 36 of the knife switch 14 and the mercury switch 31 is connected by a wire 37 to the upper terminal 38 of the knife switch 14. A reel 39 may be carried axially by the clip 30, upon which the wires 34 and 37 may coil and uncoil as the switch 31 is rotated.

A subsidiary push button switch, not shown, is connected in parallel with the switch above described, which is used only to start the oil feed pump and bring up the pressure in the oil line to normal operating pressure.

The operation of the switch is as follows:

The normal operating pressure having been set up by the oil feed pump disposes the plunger 7 in the position shown in Figure 1, the rack 11 will consequently project approximately half its length above and half below its contact with the pinion 26 and the mercury switch 31 will be in the position shown in Figures 1 and 2 and in the position shown in the Diagram B of Figure 3, in which the terminals 32 and 33 are immersed and the switch closed, so that the motor

operating the burner will continue to run. Should a rise develop in the oil line 6 due to obstruction or any other defect in the system, the plunger 7 will compress the spring 9 and 5 through the rack 11 rotate the gears 26, 27 and 28 to substantially invert the mercury switch 31 to the position shown in the Diagram A of Figure 3, thus uncovering the terminals and breaking the circuit to stop the burner from further 10 operation.

If the pressure in the oil line drops below its normal range the gears 26, 27 and 28 will be rotated in the opposite direction and will invert the mercury switch substantially to the position 15 in Diagram C of Figure 3, again breaking the circuit.

In the event of the pull cord 19 being burned and ruptured where it passes through the furnace, the tension of the spring 22 will open the 20 knife switch 14 and cause the burner to cease to function.

What I claim as my invention is:

A safety switch adapted to be operated in response to fluid pressure consisting of a mercury switch element mounted upon a horizontal axis, a cylinder adapted for connection to a source of fluid pressure, a loaded plunger adapted to 5 assume a predetermined intermediate position within the cylinder when the pressure to the cylinder is normal, said plunger having a connecting rod and a gear train operatively connecting the switch element with the connecting 10 rod whereby any upward or downward movement of the plunger from its predetermined intermediate position in the cylinder will effect a movement of the switch element towards open position, said gear train including a toothed 15 rack connected with the connecting rod, a gear in mesh with the rack, a gear rotatable in unison with the first mentioned gear and a driven gear by which the mercury switch is rotated, said driven gear being rotated by the second men- 20 tioned gear.

FREDERICK LEONARD LADE.
